UNITED STATES PATENT OFFICE

HERBERT K. BAKER, OF DETROIT, MICHIGAN, ASSIGNOR TO PENN METAL COMPANY, OF PARKERSBURG, WEST VIRGINIA, A CORPORATION OF MASSACHUSETTS

APPARATUS FOR SLITTING AND FORMING METAL SHEETS

Original application filed August 29, 1927, Serial No. 216,031. Divided and this application filed November 26, 1929. Serial No. 409,791.

This invention relates to apparatus for slitting and forming metal sheets for expanding purposes and is particularly useful in preparing "flat rib lath" blanks.

5 Among the more important objects of the invention are the increasing of the rate of production; the simplification of the apparatus with respect to construction and maintenance; and the production of lath which is 10 more efficient as a "plastic holder".

How the foregoing objects and advantages, together with others which will occur to those skilled in the art, are obtained will be clear from the following description considered in connection with the accompanying drawings which illustrate the preferred embodiment of the apparatus, and in which—

Fig. 1 is a view of a press taken from the front or feed side thereof.

20 Fig. 2 is a sectional view of the press taken as indicated by the line 2—2 of Fig. 1.

Fig. 3 is a plan view of the anvil or bottom member of the press, a portion of the stripper plate being broken away to show the 25 slitting punches therebelow.

Fig. 4 is an enlarged partial sectional view of the rib forming dies of the press taken as indicated by the line 4—4 of Fig. 2.

Fig. 5 is a view similar to Fig. 4 but taken 30 through the slitting punches as indicated by the line 5—5 of Fig. 2.

Figs. 6, 7 and 8 are views illustrating details of the formation and arrangement of the slitting punches.

35 Figs. 9 and 10 are face and cross-sectional views, respectively, of a portion of a blank as it is delivered from the slitting and forming machine of the present invention.

Figs. 11 and 12 are face and cross-sectional 40 views, respectively, of the slitted and formed flat rib lath blank of Figs. 9 and 10 after it has been expanded.

Figure 13 is an enlarged fragmentary view taken similarly to Figure 2 but illustrating 45 certain wedging and clamping devices for the slitting punches in more detail, and

Figure 14 is a view, on the same scale as Figure 13, illustrating, in plan, one of the wedge elements appearing in Figure 13.

50 Referring now to the drawings, the refer-

ence numeral 13 indicates the stationary or anvil member of the press and 14 indicates the coacting and reciprocating press member. Vertical guides 15 are secured in the anvil 55 13 and extend upwardly into the guiding holes 16 of the member 14. The member 14 of the press may be reciprocated by any suitable apparatus of well known construction (not shown).

A plurality of sets of slitting punches 17 60 and 18 are supported in the lower member of the press. These slitting punches 17 and 18 are counterparts of each other and are arranged in overlapping V-formation.

As clearly seen in Figures 7 and 8, furthermore, each punch 17 is provided with a parallel sided flattened portion adjacent the working end thereof, of reduced thickness as compared to the remainder of the punch, and this flattened portion has parallel cutting 70 edges 17a at each side thereof. The punches 18, of course, are also similarly arranged although the construction thereof is inverted or counterpart with respect to the elements designated by the numeral 17. Thus, the 75 punches 18 have parallel cutting edges 18a at each side of a reduced flattened portion towards the working ends thereof. Their cutting or slitting edges, therefore, are formed to produce pairs of parallel slits converging toward the apex of each V and, further, these edges are cut away as indicated at 19 on Figs. 6, 7, and 8 in order to terminate the slits a short distance from the apex and legs of the V. These V-shaped pairs of 80 punches are arranged in groups of four, longitudinally of the work, and the groups are arranged parallel to each other transversely of the work as clearly seen in Figure 85 1. Spacers 20 are provided between alternate groups across the press and are suitably secured in position as by bolts 21.

The groups of punches are held securely in place against the spacers 20 by U-shaped wedge members 22 which are arranged between the groups in alternate relation to the spacers 20. These U-members 22 are positioned with their legs extending horizontally, one above the other, between the alternate groups of punches and a cooperating wedge 90 95 100 wedge member 23.

element 23 extends between the legs of the member 22 from its open end. (see Figures 13 and 14, particularly, in the latter of which a wedge 22 is illustrated in top plan view). 5 Each of the elements 23 is provided with a slot 24 which engages the shoulder 25 formed on the member 26. The member 26 extends transversely of the press along the front of the groups of punches and is secured to the anvil by suitable bolts 27. A wedge 28 extends transversely of the press on the other side of the punches. This wedge has a tapered edge which cooperates with the tapered ends 29 of the members 22 to advance the 10 legs of these members between the alternate groups of punches when the wedge 28 is tightened by means of the bolts 30. It will be observed that the punches 17 and 18 are reduced at one vertical edge, as at 31 in Fig. 15 8. These reduced or tapered edges when placed adjacent provide the apex of the V of each set of punches, and the apex of the adjacent interfitting V serves to space the legs of the first V, it being noted that since the main body of the punch, i. e., the portion thereof 20 below the reduced or flattened slitting edge portion, is of greater thickness, the projection of the contacting or adjacent portions of one pair of punches between the separated portions of an adjacent pair, provides for spacing of the cutting edges (17a or 18a) from each other. The edges of the punches which are inclined in each of the two opposite directions, however, are extended parallel to 25 each other and thus provide for the interleaving of the cooperating punches so that at least a portion of each cutting edge at each side of each punch is effective in forming slits. The spacers 20 and the wedging elements 22 30 and 23 are, of course, shaped to conform to the outside configuration of each group of punches. This will be apparent from inspection of Figures 13 and 14 which illustrate, in detail, some of the wedging elements as 35 being provided with inclined or wedge surfaces 22a to contact with the inclined surfaces of the punches and also with abutments 22b arranged to engage the ends of the punches (as viewed in Figure 7 for example) 40 and thus serve to position them lengthwise of the feed in the press members. Similar serrations or abutments and wedging surfaces are provided on the spacer members. As will be clear from inspection of Figs. 45 2 and 3 the spacers 20 terminate a short distance from the tightening wedge 28, the wedge elements 23 are rigidly secured in position and terminate short of the inside of the U-members and the U-members contact with 50 the wedge 28 and are free to be advanced between the groups of punches. Thus, all the punches are securely held and spaced in pairs and groups by the tightening of one wedging element, the member 28.

55 The reciprocating member 14 carries a set

of punches 32 and 33 which are arranged and secured in identically the same manner as the set carried by the anvil member of the press. However, only three overlapping V-pairs are provided in each group and the groups are positioned in the member 14 in staggered relation to the groups in the anvil member. That is, they are so positioned as to be complementary to the lower groups. Thus, the V-pairs of an upper group fit into the V-shaped spaces formed by the spacing of the parallel punches in a lower group and the working edges of the upper and lower groups bend adjacent strands of the metal to opposite sides of the sheet. It is to be understood, of course, that the press is advanced only far enough to completely slit the metal and form the strands and that the working edges of the upper and lower punches will hardly pass each other to perform this operation.

55 The punches in the lower set are seated on a backing or wear plate 34 and may be adjusted as to height by the coating wedges 35 and 36. (See Figs. 1 and 2.) At the edges of the press are provided adjusting bolts 37 for advancing the wedges 35 and 36. Each wedge is provided with two slot-like openings which register and through which the bolts 38 extend and serve to secure the wedges as against any movement.

55 The upper set of punches is provided with a wedge adjusting mechanism identical in construction to that of the lower set. This upper wedge mechanism, however, is made of a width to conform to the narrower upper set of punches.

55 Stripper plates 39 and 40 are carried by the upper and lower press members, respectively, and have openings 41 and 42, respectively, which are shaped to conform to the configuration of the groups of punches in the respective sets. A series of springs 43 is provided along each edge of each stripper plate and serve to strip the work from the cutting edges of the punches when the press opens. Bolts 44 secured in the press and having a loose fit in the stripper plates retain the plates in position when the press is open, with their outer faces a little beyond the working edges of the punches.

55 Each press element is provided with a die positioning block 45 which is secured to its respective press element by suitable bolts 46. The forming dies are seated in grooves in the positioning blocks and are secured in place at each end by overhanging clamps 47, the same being secured to the press by the bolts 48. The die mechanism comprises two sets of upper and lower mating dies 49, 49a, and 50, 50a which are positioned alternately across the width of the press. The pairs 49, 49a have complementary working faces adapted to form the shallow bead or rib 51 in the zones or panels between the slotted strips of the sheet. (See Figs. 9-12.) The

dies of the pairs 50, 50a cooperate with each other and with the outer working edges of the pairs 49, 49a to move the narrow unslotted strip 52, which is left through the center of the slotted area, slightly out of the plane of the flat ribs and to displace the ends of the strands adjacent the ribs 51 still further out of the plane of the flat ribs. This forming operation turns both ends of the strands into a plane substantially out of the general plane of the sheet, as at 53 and 54 in Figs. 9-12. Indeed, the metal 53 at the outside ends of the strands of the pairs is turned into a plane substantially perpendicular to the general plane of the sheet. The strands will, therefore, bend more readily in expanding the blank and will not be subjected to the severe twisting strains encountered in other configurations of blanks.

20 The expanded lath is adapted to be secured in place with the displaced portions 53 adjacent the wall. Thus, when plaster is applied it will be forced between the strands behind the strips 52 and into the recesses between the ribs 51 and the portions 53. This not only provides a sure grip for plaster, but also aids in increasing the life of the lath, as substantially the entire lath will be encased in the plaster with the result that it will corrode and rust very slowly.

In operation the press is reciprocated preferably at a relatively high speed (say 400 reciprocations per minute) and the sheets to be slotted and formed are fed into the press from the right of Fig. 2. The feed is accomplished step by step in timed relation to the movement of the press, and the steps carry the sheet forward a sufficient distance to bring the metal engaged by the first V of each group of punches in the lower set into engagement with the last V of the lower groups. Thus, the slits and strands are completed throughout the entire sheet as it moves through the punches. As the sheet is advanced further the forming dies 49, 49a and 50, 50a work and swage the metal as before described to produce the ribs and the turns of the strands. Finally, the sheet may be passed out of the press and through suitable rolls and then expanded or it may be passed directly from the press to some suitable expander, such, for example, as a diverging expander.

The following summary of the method carried out by the apparatus, with the references to Figures 9 to 12 inclusive, will be of value for a complete understanding of the invention:

The blank is first slotted substantially as indicated in Figure 9 in order to produce the alternate rows of reversely inclined strands hereinbefore referred to, it being understood that at the time each portion of the blank is slotted, the blank is in the form of a flat sheet or plate of metal having no grooves, ribs or corrugations therein. The slitting operation

is carried out by first producing rows of slits in parallel zones or panels which extend longitudinally of the blank and its direction of feed. The slitting is carried out in such manner as to leave similarly arranged but unslotted panels which are in alternate relation to the slotted panels transversely of the blank. As will be apparent from inspection of Figure 9, the unslotted panels are alternately relatively wide and relatively narrow so that, in effect, the slotted panels are arranged in pairs between the panels of which the relatively narrow unslotted panels (indicated at 52) extend. Thus, each pair of slotted panels with its relatively narrow unslotted panel or strip, in effect, form an elongated slotted area (see X in Fig. 9). The relatively wide unslotted panels (subsequently formed into the ribs indicated at 51) extend longitudinally of the blank between the pairs of slotted panels. After the first transversely extending area of the blank has been slotted as specified just above, a similar set of slotted and unslotted panels is produced, the panels being arranged to continue from those already provided. This operation is carried out progressively throughout the entire length of the blank.

However, it is to be observed that the blank is progressively ribbed or grooved in certain of its panel in a manner similar to the manner in which the slotted and unslotted panels are produced, it being understood that the progressive ribbing or grooving is completed in transversely extending areas of the blank having dimensions similar to the areas referred to above. This rib or groove forming operation, furthermore, is carried out shortly after each successive area of the blank is slotted, and before the completion of the slitting operation, so that one area of the blank is being subjected to the ribbing operation simultaneously with the formation of slits in another area of the blank.

With respect to the configuration of the grooving it is to be noted that the shallow or "flat ribs" 51 are formed in the relatively wide unslotted panels extending between the pairs of reversely inclined slotted panels, or between the areas X. The grooving operation also includes a turning of the metal at the outer ends of the pairs of reversely inclined strands into a plane which is preferably substantially perpendicular to the general plane of the sheet (see reference numeral 53 Figs. 9 and 10). It is also to be noted that the areas X of the blank are grooved in such manner as to cause a slight displacement of the relatively narrow unslotted panels 52 out of the general plane of the sheet, the strands extending therefrom still farther out of the general plane of the sheet to the point indicated at 53.

The blanks having been prepared as above described may be subjected to any one of a number of expanding operations in order to

open out the sheet as indicated in Figures 11 and 12, the method of the present invention serving primarily to facilitate expansion and reduce tearing or twisting strains to which the strands are subjected as an incident to expansion.

It is to be understood, of course, that the forming dies may be changed to produce slight differences in the cross-sectional configuration of the sheet, and also that the slitting punches may be altered to produce a different design of slits. However, I prefer the foregoing embodiment.

According to the foregoing I provide an improved apparatus for producing flat rib lath blanks which not only increases speed of production, but also produces a lath which, due to the formation and bends of the strands, is economical with respect to the plaster used and is more effective as a plaster holder.

This application is a division of my pending application Serial No. 216,031, filed August 29, 1927.

I claim:

1. In apparatus of the character described, a press member, a series of groups of slitting punches mounted therein but spaced apart from each other, punch spacing and securing members between alternate groups, said spacing members being secured to said press member and said securing members comprising wedge elements adapted to secure said punches by reaction therethrough against said spacing members, together with a wedge at one end of said wedge elements for advancing said elements to securing position.

2. Apparatus for slitting metal sheets for expansion including cooperating press members, groups of cooperating slitting punches mounted in the press members in position to interleave with each other upon relative actuation of the press members, said interleaving punches having substantially flat portions with cutting edges at each side thereof and the end portions of the cutting edges of at least some of said punches being tapered-off away from the mean plane in which the slitting is effected.

3. Apparatus for slitting metal sheets for expansion including cooperating press members, groups of cooperating slitting punches mounted in the press members in position to interleave with each other upon relative actuation of the press members, said interleaving punches having substantially flat portions with cutting edges at each side thereof and the cutting edges of at least one of said punches being formed in parallel sections extended at an angle to each other.

4. Apparatus for slitting metal sheets including cooperating press members, and cooperating slitting punches mounted in the press members, said punches including substantially flat portions at least some of which are provided with slitting edges at each side

thereof, at least some of said punches having end portions of their slitting edges tapered-off away from the mean plane in which the slitting is effected and said cooperating punches being relatively positioned in the press members to interleave upon actuation thereof, whereby slitting is effected at each one of said tapered-off slitting edges.

5. In apparatus of the character described, cooperating press members, a group of slitting punches mounted in one of the press members, at least some of said punches having substantially flat portions with slitting edges at each side thereof, the punches of the group being spaced from each other with their slitting edges extended along parallel lines to provide for interleaving of slitting punches mounted in a cooperating press member, and a group of slitting punches mounted in a cooperating press member, at least one of the punches of the last mentioned group having a substantially flat portion with slitting edges at each side thereof formed in sections each of which includes a pair of parallel slitting edges extended at an angle to those of another section.

6. A slitting punch for use in apparatus of the character described, said punch having a parallel sided flattened portion with a slitting edge at each side thereof divided into a plurality of sections extended at an angle to each other, the sections of the edges being arranged in parallel pairs.

7. Apparatus for slitting and ribbing metal sheets including cooperating relatively movable press members adapted to the intermittent feed of sheets therethrough, groups of cooperating slitting elements mounted in the press members, groups of cooperating ribbing elements mounted in the press members beyond the slitting elements with respect to the direction of feed through the apparatus and spaced from said slitting elements, and stripper mechanisms associated with the press members and having cooperating sheet engaging surfaces disposed in the space between the slitting and ribbing elements, said mechanisms being yieldingly mounted in positions to engage the sheets during movement of the press members toward each other before engagement of the cooperating slitting elements.

8. Apparatus for slitting metal sheets including cooperating relatively movable press members adapted to the intermittent feed of sheets therethrough, a plurality of spaced groups of slitting punches mounted in each press member, the punches of the groups being spaced from each other and relatively disposed to interleave upon actuation of the press members, and cooperating stripper mechanisms associated with the press members and each having relatively large cooperating sheet gripping surfaces disposed beyond the cooperating groups of in-

terleaving punches with respect to the direction of feed through the apparatus, said mechanisms being resiliently mounted to provide for engagement of the sheets by said surfaces during movement of the press members toward each other and before interleaving of the cooperating punches.

9. Apparatus for slitting metal sheets including cooperating relatively movable press members adapted to the intermittent feed of sheets therethrough, a plurality of spaced groups of slitting punches mounted in each press member, the punches of the groups being spaced from each other and relatively disposed to interleave upon actuation of the press members, and cooperating stripper mechanisms associated with the press members and each having relatively large cooperating sheet gripping surfaces disposed beyond the cooperating groups of interleaving punches with respect to the direction of feed through the apparatus, said mechanisms being resiliently mounted to provide for engagement of the sheets by said surfaces during movement of the press members toward each other and before interleaving of the cooperating punches, said surfaces being so positioned with respect to the groups of punches and being so dimensioned with respect to the groups of slits produced by the groups of punches as to engage, at each operation of the press members, portions of the blanks including groups of slits produced by a preceding operation.
10. Apparatus for slitting metal sheets including cooperating relatively movable press members adapted to the intermittent feed of sheets therethrough, a plurality of spaced groups of slitting punches mounted in each press member, the punches of the groups being spaced from each other and relatively disposed to interleave upon actuation of the press members, and cooperating stripper mechanisms associated with the press members and each having relatively large cooperating sheet gripping surfaces disposed beyond the cooperating groups of interleaving punches with respect to the direction of feed through the apparatus, said mechanisms being resiliently mounted to provide for engagement of the sheets by said surfaces during movement of the press members toward each other and before interleaving of the cooperating punches, said surfaces being so positioned with respect to the groups of punches and being so dimensioned with respect to the groups of slits produced by the groups of punches as to engage, at each operation of the press members, portions of the blanks including the groups of slits produced by the immediately preceding operation.

11. Apparatus for slitting metal sheets including cooperating relatively movable press members adapted to the intermittent feed of sheets therethrough, groups of cooperat-

ing slitting punches mounted in the press members, and a plate-like stripper member associated with each of the press members, each of said stripper members having an opening therein substantially conforming to the outside configuration of the group of punches mounted in the associated press member, and resilient mounting means for urging said stripper members toward each other to grip the sheets during movement of the press members toward each other before the engagement of the cooperating slitting punches.

12. Apparatus for slitting metal sheets for expansion into stranded lath including cooperating relatively movable press members adapted to the intermittent feed of sheets therethrough, a plurality of groups of cooperating slitting punches mounted in each one of the press members, each punch having a flattened portion with a slitting edge at each side thereof inclined with respect to the direction of feed through the apparatus, there being a plurality of groups of punches inclined in each of two opposite directions and the punches of each of said groups being mounted with their slitting edges arranged parallel to but spaced from each other, the punches of the groups being relatively positioned and arranged in the press members to interleave upon actuation thereof to produce a substantially equal number of slits inclined in each direction.

13. Apparatus for slitting metal sheets for expansion into stranded lath including cooperating relatively movable press members adapted to the intermittent feed of sheets therethrough, said press members having cavities or recesses therein adapted to receive groups of slitting punches, groups of cooperating punches in said cavities, the punches of each group having flattened portions with cutting edges at each side thereof spaced from the cutting edges of adjacent punches to provide for interleaving of the cooperating punches, means for spacing punches of each group from each other in parallel relationship, and wedge devices in said cavities reacting against cavity walls to secure the groups of punches in operative positions as units.

14. Apparatus for slitting metal lath including in combination with a press member, a group of slitting punch elements each having a pair of parallel cutting edges formed at opposite sides thereof, the punches of said group being arranged in pairs, with the cutting edges of one spaced from and angled with respect to the cutting edges of the other, the punches of each pair further having interengaging portions at a point toward one end of the cutting edges thereof, and the pairs of punches being arranged in serially overlapping formation with the interengaging

portions of one pair projected between separated portions of an adjacent pair.

15. Apparatus for slitting metal lath including in combination with a press member, 5 a group of slitting punch elements each having a pair of parallel cutting edges formed at opposite sides thereof, the punches of said group being arranged in pairs, with the cutting edges of one spaced from and angled 10 with respect to the cutting edges of the other, the punches of each pair further having interengaging portions at a point toward one end of the cutting edges thereof, and the pairs of punches being arranged in serially 15 overlapping formation with the interengaging portions of one pair projected between separated portions of an adjacent pair, together with means for mounting the punches of said group including a serrated member 20 arranged at one side of the group to contact with one punch of each pair, and an additional and similar serrated member arranged at the opposite side of the group, with means for relatively moving said serrated members 25 to secure the punches in operative position by a wedging action.

16. A punch of the character described comprising a generally flattened member having a bevelled edge at one side thereof, 30 a portion having parallel sides but of reduced thickness along an edge extended at right angles to the bevelled edge, and parallel cutting edges formed at opposite sides of the portion last mentioned.

35 17. Apparatus for slitting metal sheets including cooperating press members adapted to the intermittent feed of sheets therethrough; a group of punches mounted in one of said members, each of said punches 40 comprising a generally flattened member having a bevelled edge at one side thereof, a portion having parallel sides but of reduced thickness along an edge extended at right angles to the bevelled edge, and parallel 45 cutting edges formed at opposite sides of the portion last mentioned, the punches of said group being arranged in pairs with their bevelled edges juxtaposed and with the opposite edges spaced from each other, and the 50 pairs of punches being arranged in serially overlapping formation with the juxtaposed portions of one pair projecting into the space between the punches of an adjacent pair; and cooperating punch elements mounted in the 55 other press member.

18. In apparatus of the character described, a pair of cooperating press members adapted to the intermittent feed of sheets therethrough; a group of punches mounted 60 in one of said press members, the punches of said group comprising generally plate-like punch elements each having a flattened portion toward the working side of the press member with a pair of parallel cutting edges 65 at each side thereof, and each element fur-

ther having a portion thereof projected laterally of its flattened portion toward one end of its cutting edges, and said elements being arranged in pairs with said projecting portions facing but spaced from each other and with portions thereof toward the opposite ends of the cutting edges juxtaposed, and the several pairs of the group being arranged in overlapping formation with the juxtaposed portions of one pair extended between the spaced portions of an adjacent pair; and cooperating punch elements mounted in the other press member in position to interleave with the overlapping portions of the elements first mentioned.

19. In apparatus of the character described, a pair of cooperating press members adapted to the intermittent feed of sheets therethrough; a group of slitting punches mounted in one press member and comprising one set of punch elements at least partially overlapping transversely of the feed through the apparatus with flattened portions having cutting edges at each side thereof inclined in one direction with respect to the feed path of the sheets, and another set of similarly overlapping punch elements reversely inclined with respect to said path, the punches of the two sets being arranged in pairs with their converging portions contacting with each other and with their diverging portions spaced from each other; and cooperating punch elements mounted in the other press member.

20. In apparatus of the character described, a pair of cooperating press members adapted to the intermittent feed of sheets therethrough; a group of slitting punches mounted in one press member and comprising one set of punch elements at least partially overlapping transversely of the feed through the apparatus with flattened portions having cutting edges at each side thereof inclined in one direction with respect to the feed path of the sheets, the overlapping portions of said elements being provided with means for spacing the flattened portion of one element from that of an adjacent element, and another set of similarly overlapping punch elements reversely inclined with respect to said path, the punches of the two sets being arranged in pairs with their converging portions contacting with each other and with their diverging portions spaced from each other; and cooperating punch elements mounted in the other press member in position to interleave with the spaced overlapping portions of the punch elements first mentioned.

21. In apparatus of the character described, a pair of cooperating press members adapted to the intermittent feed of sheets therethrough; a group of slitting punches mounted in one press member and comprising one set of punch elements at least par-

tially overlapping transversely of the feed through the apparatus with flattened portions having cutting edges at each side thereof inclined in one direction with respect to the feed path of the sheets, at least the overlapping portions of said slitting edges being tapered-off away from the mean plane in which the slitting is effected, and another set of similarly overlapping punch elements re-
5 versely inclined with respect to said path, the punches of the two sets being arranged in pairs with their converging portions contacting with each other and with their diverging portions spaced from each other; and co-
10 operating punch elements mounted in the other press member.

22. In apparatus of the character described, a pair of cooperating press members adapted for intermittent feed of the sheets
20 therebetween, groups of slitting punches in each of the press members arranged to interleave upon actuation thereof, the plurality of groups of punches in each press member being separated from each other transversely of the feed of sheets through the apparatus to provide unslotted strips of metal therein, and the groups of punches each including a plurality of punches having cutting edges inclined with respect to the direction of feed
25 through the apparatus, and a stripper mechanism including an element extended lengthwise of the feed of the apparatus between said transversely spaced groups of punches.

23. Apparatus of the character described
35 including in combination with a pair of cooperating press members adapted to the intermittent feed of sheets therethrough, a group of slitting punches in one of the press members comprising punch elements having slitting edges at each side thereof, means for spacing the punches of the group from each other with the cutting edges thereof extending along parallel lines, said parallel punches having their slitting edges inclined with respect to the direction of feed through the apparatus with at least a portion of a slitting edge of one punch spaced from the slitting edge of an adjacent punch transversely of the direction of feed to provide for the production of a plurality of slits in at least one row extending lengthwise of the feed through the apparatus at each press operation, and cooperating slitting punch elements mounted in the other press member arranged in a similar inclined fashion to interleave with the punches of the first group.

25. Apparatus of the character described including in combination with a pair of cooperating press members adapted to the intermittent feed of sheets therethrough, a cavity in one of the press members, a group of slitting punches comprising punch elements having slitting edges at each side thereof, means for spacing the punches of the group from each other with the cutting edges thereof extending along parallel lines, said parallel punches having their slitting edges inclined with respect to the direction of feed through the apparatus with at least a portion of a slitting edge of one punch spaced from the slitting edge of an adjacent punch transversely of the direction of feed to provide for the production of a plurality of slits in at least one row extending lengthwise of the feed through the apparatus at each press operation, there being a plurality of such groups of slitting punches mounted in said cavity in spaced relation, a wedge device for securing the punches of at least two groups, as units, in said cavity, and cooperating slitting punch elements mounted in the other press member arranged in a similar inclined fashion to interleave with the punches of the first group.

26. In combination, a pair of cooperating press members, in one press member a set of groups of parallel sided parallel punch elements inclined in one direction with respect to the direction of feed and a set of groups of parallel sided parallel punch elements inclined in an opposite direction with respect to the direction of feed, the groups of each set being positioned in a row transversely of the direction of feed, there being punch elements of each inclination spaced, in the direction of feed, substantially more than half the length of the cutting edge of such element but with cutting edges of adjacent punches overlapping each other in spaced relation generally transversely of the direction of feed, and cooperating sets of groups of punch elements positioned in the other press mem-

ber to register with the spaces between the cutting edges last mentioned and thus to interleave with the punches first mentioned upon actuation of the press.

- 5 27. Apparatus of the character described including in combination with a pair of cooperating press members adapted to the intermittent feed of sheets therethrough, a plurality of closely associated slitting punches arranged for mounting in one of the press members as a unitary group, said punches including separate punch elements each having a pair of cutting edges spaced from the cutting edges of adjacent punches in the group and each further having a plate-like mounting or securing portion extended well away from the slitting edges thereof, there being a plurality of such groups of slitting punches mounted in the press member and spaced 10 from each other in a substantially parallel relationship transversely of the feed through the apparatus, means for securing the punch elements of one group in operative position, as a unit, including a device disposed in a 15 space between adjacent groups and adapted to grip the mounting portions thereof, and cooperating slitting punches mounted in the other press member in position to register with spaces between the slitting edges of the 20 punches first mentioned and thus to interleave upon actuation of the press members.

- 25 28. Apparatus of the character described including in combination with a pair of cooperating press members adapted to the intermittent feed of sheets therethrough, a group of closely associated slitting punches including separate plate-like punch parts each having a flattened portion with a slitting edge at each side thereof and each further having a 30 securing or mounting portion extended well away from the cutting edge portion, means cooperating with said mounting portions for mounting the punches of said group in close association with each other in one of said 35 press members but with each cutting edge thereof parallel to the cutting edge of an adjacent punch and further with adjacent cutting edges of adjacent punches spaced from each other transversely of the feed through 40 the apparatus, and cooperating slitting punch parts mounted in the other press member in position to register with the spaces between said adjacent edges of adjacent punches and thus to interleave upon actuation of the press 45 members.

50 In testimony whereof I have hereunto signed my name.

HERBERT K. BAKER.
